(57) **CLAIM**

The ornamental design for an oval dentifrice patch, as shown
and described.

DESCRIPTION

FIG. 1 is a perspective view of an oval dentifrice patch;
FIG. 2 is a front view thereof;
FIG. 3 is a left side view thereof;
FIG. 4 is a rear view thereof;
FIG. 5 is a right side view thereof;
FIG. 6 is a top plan view thereof;
FIG. 7 is a bottom plan view thereof;
FIG. 8 is a perspective view of a second embodiment of an
oval dentifrice patch;
FIG. 9 is a front view thereof;
FIG. 10 is a left side view thereof;
FIG. 11 is a rear view thereof;
FIG. 12 is a right side view thereof;
FIG. 13 is a top plan view thereof;
FIG. 14 is a bottom plan view thereof;
FIG. 15 is a perspective view of a third embodiment of an
oval dentifrice patch;
FIG. 16 is a front view thereof;
FIG. 17 is a left side view thereof;
FIG. 18 is a rear view thereof;
FIG. 19 is a right side view thereof;
FIG. 20 is a top plan view thereof;
FIG. 21 is a bottom plan view thereof;
FIG. 22 is a perspective view of a fourth embodiment of an
oval dentifrice patch;
FIG. 23 is a front view thereof;
FIG. 24 is a left side view thereof;
FIG. 25 is a rear view thereof;
FIG. 26 is a right side view thereof;
FIG. 27 is a top plan view thereof;
FIG. 28 is a bottom plan view thereof;
FIG. 29 is a perspective view of a fifth embodiment of an
oval dentifrice patch;
FIG. 30 is a front view thereof;
FIG. 31 is a left side view thereof;
FIG. 32 is a rear view thereof;
FIG. 33 is a right side view thereof;
FIG. 34 is a top plan view thereof; and,
FIG. 35 is a bottom plan view thereof.

The broken lines illustrate the environment of the oval
dentifrice patch and form no part of the claimed design.
